STENOGRAPHER'S PENCIL STAND

Florence Krempler, Stapleton, Staten Island,
N. Y.

Application March 29, 1939, Serial No. 264,734

1 Claim. (Cl. 311—101)

This invention relates to stenographers' pencil stands.

Desks and tables upon which the stenographer writes are rarely available, and tables that are available are in most cases too high for stenographic use. Furthermore, writing in the stenography book while keeping the book on the knee increases shorthand speed. In most cases, stenographers resort to knee writing instead of desk writing. In such cases, the employer usually sits at the desk and the stenographer takes down the dictation a short distance away. The same holds true in most conferences, directors meetings, and the like, where the stenographer takes down matter dictated by many men gathered in the room, and in which case she is compelled to keep her pencils clutched in her left hand, (causing perspiration and hindrance through this inconvenience) or hurriedly places 10 pencils in whatever space remains beside her on the chair. It often takes stenographers a long time to retrieve pencils from awkward places while conferences have been delayed and much of the dictation missed.

It is therefore an object of this invention to provide a stenographer's pencil stand which may be placed on the floor near the stenographer's chair wherever the chair is placed, to support a plurality of sharpened pencils in such position that the pencils may be readily removed from the stand, the construction being furthermore provided with a place to put dull pencils, so that the stenographer will always have a sharpened pencil at a place where she can easily get at 20 without loss of time. Such a time saving device will result in greater efficiency for stenographers, and consequently, more satisfactory work for employers due to the added convenience which stenographers will have in note taking.

The stand may be made of metal or other solid substance in order that its weight might insure firmness when it is placed on the floor.

A further object of this invention is to provide a strong, rugged and durable pencil stand of the character described which shall be relatively inexpensive to manufacture, easy to use, attractive in appearance, and yet practical and efficient to a high degree in use.

Other objects of this invention will in part be obvious and in part hereinafter pointed out.

The invention accordingly consists in the features of construction, combination of elements, and arrangement of parts which will be exemplified in the construction hereinafter described,

and of which the scope of application will be indicated in the following claim.

In the accompanying drawing, in which is shown one of the various possible illustrative embodiments of this invention.

Fig. 1 is a side elevational view of a pencil stand, embodying the invention, with six sharpened pencils shown in position ready for use, and one dull pencil shown in dotted lines in the position where it is placed after use;

Fig. 2 is a top plan view of the top of the stand shown in Fig. 1;

Fig. 3 is a side elevational view of the upper portion of the pencil stand, at a different angle than shown in Fig. 1; and

Fig. 4 is a cross-sectional view taken on line 4—4 of Fig. 2.

Referring now in detail to the drawing, 10 designates a stenographer's pencil stand embodying the invention. The same may be made 20 of wood, metal, or any other suitable substance, and should be light enough so that the same may be readily carried from one place to another, and yet heavy enough so as not to easily topple over.

The stand 10 comprises a base 11 contacting the floor 12. Extending upwardly from the center of the base 11, is a post 13. On top of the post is supported a top member 14. The top member 14 may be annular, as shown in Fig. 2 30 of the drawing, and has a substantially rectangular top flat surface 15, and a plurality of downwardly and outwardly inclined surfaces 16.

Extending upwardly from the top surface 15 are a pair of central, aligned, upwardly extending 35 spaced ridges or walls 17. Said ridges 17 are of equal length and height, there being a central space 18 therebetween. Extending upwardly from said flat surface 15, on the opposite sides of the ridges 17, are pairs of spaced, aligned 40 ridges 19, parallel to said ridges 17. The ridges 19 are similar to the ridges 17 in length and height, there being a space 20 between each pair of ridges 19.

The ridges 17 divide the surface 15 into two 45 portions, one to receive sharpened pencils 21, and one to receive dull pencils 22.

The height of the stand may be twenty-five inches. The surface 15 may be six inches long and five inches wide. The ridges or raised portions 17 and 19 may be one-half inch in height, and the corners thereof are preferably rounded. I have found that with these dimensions, six sharpened pencils 21 can be conveniently placed 55

on one side of the ridges 17, parallel to said ridges.

Although the above dimensions may be considered as the standard size for regular office use, larger types can be made to accommodate a greater number of pencils. The newly sharpened pencils are laid in one section, and as each pencil becomes dull through use, it is placed in another section, and a new one quickly picked up from the first section. With this construction there will be no hesitation in deciding which pencils have been used and which have not, as is the case with pencils which are sprawled on the desk, thus retarding speed in the dictating session.

15 The stand should be so placed so that the section with the sharpened pencils is nearer the stenographer's right hand. A stand of this kind conveniently located on the right hand side of the stenographer will insure the removal of former pencil handicaps and make for less confusion and greater speed, in a more orderly working system.

20 The easiest and most convenient way to use the six pencils on the stand, is to use the sixth pencil, or the one nearest the middle raised ridges first. The fingers of the stenographer pass through the space between the ridges 17 when taking up a newly sharpened pencil. After the 25 sixth pencil has been used it is placed in the section for the dull pencils, and the fifth pencil which is now nearest to the ridges 17 is taken up. It is preferable not to fill up the section for

the newly sharpened pencils entirely, so as to leave some room for the stenographer's fingers when a sharpened pencil is picked up.

It will thus be seen that there is provided a device in which the several objects of this invention are achieved, and which is well adapted to meet the conditions of practical use.

As various possible embodiments might be made of the above invention, and as various changes might be made in the embodiment above set forth, it is to be understood that all matter herein set forth or shown in the accompanying drawing is to be interpreted as illustrative and not in a limiting sense.

Having thus described my invention, I claim as new and desire to secure by Letters Patent:

A stenographer's pencil stand comprising a base, a post extending upwardly therefrom, a top member at the top of the post, said top member having a substantially rectangular flat surface, and surfaces inclined downwardly and outwardly from said flat surface, said flat surface being formed with a central pair of spaced, aligned ridges, and pairs of spaced, aligned ridges on opposite sides of said first pair of spaced, aligned ridges, and parallel thereto and co-extensive therewith, all of said ridges being of square height, said pairs of aligned ridges being disposed at a pair of opposite ends of said flat surface, and the outer ends of each pair of ridges being located at the other pair of opposite ends of said flat surface.

FLORENCE KREMLER.
